United States Patent

Des. 234,565
Patented Mar. 25, 1975

234,565

LEG UNIT

William C. Andrus, Wyoming, Mich., assignor to
Steelcase Inc., Grand Rapids, Mich.

Filed Apr. 23, 1973, Ser. No. 353,322

Term of patent 14 years

Int. Cl. D6—06

U.S. Cl. D6—194

FIG. 1.

FIG. 5

FIG. 2.

FIG. 3.

FIG. 4.

FIG. 6.

FIG. 7

FIG. 8.

FIG. 1 is a perspective view of a leg unit embodying the design of the invention;

FIG. 2 is a side elevational view of the leg unit;

FIG. 3 is a front elevational view of the leg unit;

FIG. 4 is a top plan view of the leg unit;

FIG. 5 is a generally rear perspective view of the leg unit;

FIG. 6 is a cross-sectional view taken along plane VI—VI of FIG. 2;

FIG. 7 is a cross-sectional view taken along plane VII—VII of FIG. 2; and

FIG. 8 is a cross-sectional view taken along plane VIII—VIII of FIG. 2.

I claim:

The ornamental design for a leg unit, substantially as shown.
